(57) **CLAIM**

The ornamental design for a head-mounted display as shown and described.

DESCRIPTION

1. Head-mounted display

1.1 : Perspective

1.2 : Front

1.3 : Back

1.4 : Left

1.5 : Right

1.6 : Top

1.7 : Bottom

1.8 : Perspective

1.9 : Shrink state reference view

1.10 : Shrink state reference view

Image and video display equipment.
